UNITED STATES PATENT OFFICE.

EDWARD GERMAIN, OF SAGINAW, MICHIGAN.

DESIGN FOR A MANTEL.

SPECIFICATION forming part of Design No. 21,156, dated November 10, 1891.

Application filed October 14, 1891. Serial No. 408,724. Term of patent 7 years.

To all whom it may concern:

Be it known that I, EDWARD GERMAIN, of Saginaw, in the State of Michigan, have invented and produced a new and original Design for Mantels, of which the following is a specification.

In the accompanying drawings, Figure 1 is a front elevation of the mantel. Fig. 2 is a transverse sectional elevation of the same. Fig. 3 is a horizontal section through one of the pilasters.

The two last-named views are necessary in order to show more completely the outline and configuration of the parts.

a are the pilasters. *b* are the plinths; *c*, the caps; *d*, the frieze; *e*, the mantel-board; *f*, the grounds, and *g* the fire-strips. The plinths have beveled top edges *h*. The pilasters have beveled side edges *i* and raised molded centers *j*, which extend from the caps above to the plinths below. The configuration of the molding is shown clearly in the cross-sectional view, Fig. 3. The caps have beveled side and bottom edges *k* and two longitudinal

parallel grooves *l* in their faces, which grooves terminate before reaching the top and bottom edges of the caps. The frieze has a raised panel *m*, which extends between the caps, and is formed with beveled edges *n* and two grooves *o* conterminous with the bevels *n*. 30

At the bottom of the frieze is a molding *p*. *r* is a fitting-strip at the upper part of the frieze, flush with the caps and having a beveled lower edge *r'*, and *s* is a molding beneath the mantel-board. 35

The fire-strips *g*, as well as the outer side strips of the grounds *f*, have molded fronts, and the mantel-board has a molded edge.

What I claim, and desire to secure by Letters Patent, is—

The design for a mantel, as herein described and shown.

In testimony whereof I affix my signature in presence of two witnesses.

EDWARD GERMAIN.
